(57) **CLAIM**

The ornamental design for a charger, as shown and described.

DESCRIPTION

FIG. 1 is a top front perspective view of the charger, showing the new design;

FIG. 2 is a bottom rear perspective view of the charger thereof;

FIG. 3 is a front elevational view of the charger thereof;

FIG. 4 is a rear elevational view of the charger thereof;

FIG. 5 is a left side elevational view of the charger thereof;

FIG. 6 is a right side elevational view of the charger thereof;

FIG. 7 is a top plan view of the charger thereof; and,

FIG. 8 is a bottom plan view of the charger thereof.

The broken lines depict portions of the Charging Plug Station that form no part of the claimed design.

1 Claim, 8 Drawing Sheets
